US0D1086295S

(12) **United States Design Patent** (10) Patent No.: **US D1,086,295 S**
(45) Date of Patent: ** Jul. 29, 2025

(54) **LITTLE GENIUS EDUCATIONAL PUZZLE**

(71) Applicant: **Magdalena Henrietta Elizabetha Pieters**, Pretoria east (ZA)

(72) Inventor: **Magdalena Henrietta Elizabetha Pieters**, Pretoria east (ZA)

(**) Term: **15 Years**

(21) Appl. No.: **35/510,419**

(22) Filed: **Dec. 30, 2019**

(80) **Hague Agreement Data**

Int. Filing Date: **Dec. 30, 2019**

Int. Reg. No.: **DM/210288**

Int. Reg. Date: **Dec. 30, 2019**

Int. Reg. Pub. Date: **Sep. 25, 2020**

(51) **LOC (15) Cl.** 21-01

(52) **U.S. Cl.**

USPC **D21/478**

(58) **Field of Classification Search**

USPC D21/478, 479, 480, 484, 491, 498, 707, D21/713; D19/59-64, 39-40

CLAIM

The ornamental design for the little genius educational puzzle as shown and described.

DESCRIPTION

The patent or application file contains at least one drawing executed in color. Copies of this patent or patent application publication with color drawing(s) will be provided by the Office upon request and payment of the necessary fee.

Fig. 1.1: Top perspective view of layered “little genius educational puzzle” showing my new design, showing some pieces removed from every puzzle layer.

Information puzzle; lower layers are smaller and more complex; conveys progressive information and understanding.
